United States Patent Office.

JOHN JOSEPH CLOES, OF LIEGE, BELGIUM, ASSIGNOR TO EDWARD DE BEAUMONT, OF SAME PLACE.

Letters Patent No. 101,826, dated April 12, 1870.

IMPROVEMENT IN BREECH-LOADING FIRE-ARMS

The Schedule referred to in these Letters Patent and making part of the same.

To all whom it may concern:

Be it known that I, JOHN JOSEPH CLOES, of Liege, in the Kingdom of Belgium, have invented a new Improvement in Breech-loading Fire-Arms; and I do hereby declare the following, when taken in connection with the accompanying drawings and the letters of reference marked thereon, to be a full, clear, and exact description of the same, and which said drawings constitute part of this specification, and represent in—

Figure 1, a side view;

Figure 2, a top view;

Figure 3, a vertical central section; and in

Figure 4, a detached view of the cocking-cam.

This invention relates to an improvement in the arm known as the needle-gun, and consists in the arrangement of the mainspring within the lever which operates the movable breech and hammer.

A is the rear end of the barrel, formed to receive the cartridge-shell, and extending back to form a guide for the combined lock and the movable breech secured to the wood stock by a screw through the tail-piece B.

C is the movable breech, through which the hammer or needle d extends, the needle being formed or made a part of the head D, also forming a spindle, f, around which is arranged a cylinder, n, to which a handle or lever, E, is fixed, to turn the said cylinder on the spindle f, and also to serve as a means for drawing the breech back as denoted in broken lines, fig. 1.

The breech is cut away so that the said handle E may be turned down, as denoted in broken lines, fig. 2.

Within the handle E is arranged the mainspring a, supported in the handle, and working in an annular groove, m, in the spindle f, so that, in whatever position the said handle stands, the spring will bear upon the spindle.

F is the trigger and G the sear, formed as part of a spring, g, underneath the barrel.

The operation of these parts is as follows:

The position of the lever E, when the arm is discharged, is as denoted in broken lines, fig. 2. To draw back the breech for charging, raise the arm, as denoted in figs. 1 and 3, (the cylinder n being connected to the movable breech by a connection, H, and screw, h, the said screw working in a groove, i, on the breech,) in thus raising the arm, a cam, s, on the cylinder operates to force back the head D, and with it the needle d, as denoted in fig. 3, the cylinder holding the hammer back while the handle is turned up. In this position the movable breech is brought back with the whole lock mechanism, as denoted in broken lines, fig. 1; the cartridge is then inserted in the usual manner for breech-loaders, the breech-block and mechanism returned, and the handle E turned down at right angles, as denoted in fig. 2, which leaves the hammer-head D caught upon the sear G, as seen in fig. 3, from which it is released by operating the trigger in the usual manner; but until the arm E is thus turned down, the hammer cannot be discharged, inasmuch as it will be held by the cylinder n.

A position of half-cock is held by a lock, L. A cartridge-extractor, consisting of a catch, t, is applied to the movable breech, acting in the usual manner, to withdraw the cartridge-shell.

I claim as my invention—

The combination of the movable breech C and hammer D, constructed with the spindle f and needle d, with the cam cylinder n and handle E, inclosing the mainspring a, and trigger F, and sear G, the whole constructed and arranged to operate in the manner described.

JOHN JOSEPH CLOES.
